United States Patent Office.

M. C. HEPTINSTALL, OF ENFIELD, NORTH CAROLINA.

Letters Patent No. 92,530, dated July 13, 1869.

FIRE-TONGS.

The Schedule referred to in these Letters Patent and making part of the same.

To all whom it may concern:

Be it known that I, M. C. HEPTINSTALL, of Enfield, in the county of Halifax, and State of North Carolina, have invented a new and useful Improvement in Tongs; and I do hereby declare that the following is a full, clear, and exact description thereof, which will enable others skilled in the art to make and use the same, reference being had to the accompanying drawing, forming part of this specification.

The object of this invention is to provide an improved construction and arrangement of fire-tongs, that will prevent the legs from having lateral play at the gripping-ends, as is common with tongs as at present constructed, especially when worn at the joint.

Figure 1 represents a side view, partly broken, of my improved tongs, and

Figure 2 represents a detail view of the same.

Similar letters of reference indicate corresponding parts.

I increase the breadth of that prong which terminates in the handle, immediately in rear of the pivot joint, as shown at *a-a*, and in this inward part I form a recess, *b*.

I also provide a rear extension, *C*, upon the short prong, to work in the said recess; and

I close the said projection into the recess by a plate, *d*, fitting snugly against the face of the said projection, one end of the plate *d* being secured by a screw, *e*, and the other by the pivot-bolt *f*.

This long projection, fitting between the two sides of the said recess, effectually prevents the lateral play of the gripping-ends of the prongs, common to tongs, as now constructed, without the projection and recess, as above described.

Having thus described my invention,

What I claim as new, and desire to secure by Letters Patent, is—

The combination with tongs having the recess *b* in one prong, and the projection *c* on the other, of the plate *d*, when secured thereto by the pivot-bolt *f* and a screw, *e*, substantially as specified.

M. C. HEPTINSTALL.
